(57) **CLAIM**

The ornamental design for a pivotal bracket for balusters, as shown and described.

DESCRIPTION

FIG. 1 is a perspective view from above of pivotal bracket for balusters showing our new design;

FIG. 2 is a first side elevational view thereof;

FIG. 3 is a second side elevational view thereof;

FIG. 4 is a first end elevational view thereof;

FIG. 5 is a second end elevational view;

FIG. 6 is a top plan view thereof; and,

FIG. 7 is a second side elevational view showing parts in relatively pivoted condition.
